[57] CLAIM

The ornamental design for a lounge seat, substantially as shown and described.

DESCRIPTION

FIG. 1 is a perspective view of a lounge seat embodying my new design;

FIG. 2 is a perspective view of a second embodiment of the lounge seat shown in FIG. 1;

FIG. 3 is an exploded perspective view of the lounge seat shown in FIG. 1; and

FIG. 4 is an exploded perspective view of the lounge seat shown in FIG. 2.

The rear surfaces of the lounge seat not visible in FIGS. 1 and 2 are substantially plain and unornamented.
